(57) **CLAIM**

The ornamental design for a cylinder head for internal combustion engines, as shown and described.

DESCRIPTION

FIG. 1: a front elevation view of the cylinder head for internal combustion engines;

FIG. 2: a rear elevation view of the cylinder head for internal combustion engines;

FIG. 3: a right side elevation view of the cylinder head for internal combustion engines;

FIG. 4: a left side elevation view of the cylinder head for internal combustion engines;

FIG. 5: a top plan view of the cylinder head for internal combustion engines;

FIG. 6: a bottom plan view of the cylinder head for internal combustion engines;

FIG. 7 is a front perspective view of the cylinder head for internal combustion engines as seen from the right upper side thereof;

FIG. 8 is a front perspective view of the cylinder head for internal combustion engines as seen from the left lower side;

FIG. 9 is a rear perspective view of the cylinder head for internal combustion engines as seen from the left upper side; and,

FIG. 10 is a rear perspective view of the cylinder head for internal combustion engines as seen from the right lower side.
